UNITED STATES PATENT OFFICE

2,552,214

SLIDE ACTION ATTACHMENT FOR SHOT-
GUNS AND RIFLES

Jerry W. Raymond, Wenatchee, Wash.

Application February 8, 1950, Serial No. 143,107

5 Claims. (CL 42—16)

1

This invention relates to a slide action attachment for shotguns and rifles.

An object of the invention is to provide efficient and novel means for actuating the sliding bolt of a gun, such as a rifle, shotgun, etc.

Another object of the invention is the production of a bolt action device which can be applied to a gun at the time of manufacturing the gun, or can be applied at any time after the gun has been manufactured.

A still further object of the invention is the construction of an apparatus which is easily operated and which will be positive in action for producing best results.

This application disclosed efficient and novel improvements upon the patentable structure disclosed in my co-pending allowed application, Serial No. 19,811, filed April 8, 1948, Patent No. 2,499,878.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a top plan view of the attachment as it appears when the gun is in a closed or firing condition, while

Figure 2 is a view in side elevation of the same.

Figure 3 is a top plan view showing the gun and the attachment in an open position, while

Figure 4 is a view in side elevation of the same.

Figure 5 is an enlarged fragmentary horizontal sectional view taken on line 5—5, Fig. 2, and looking in the direction of the arrows.

Figure 6 is a transverse sectional view taken on line 6—6, Fig. 5, and looking in the direction of the arrows.

Figure 7 is an enlarged sectional view taken on line 7—7, Fig. 1, and looking in the direction of the arrow.

Figure 8 is a view partly in section and partly in elevation of the ball and link device.

Figure 9 is a fragmentary view in elevation of a gun stock and barrel, showing the hand grip device.

Referring to the drawings, the gun 1 is of the usual type, comprising a stock 1 and a gun barrel 2. The gun is provided with a sliding bolt 3 to which is fixedly secured a laterally extending lever 4. On the outer end of lever 4 is fixedly secured ball 5.

The attachment for actuating the sliding bolt 3 comprises a track 6, which is shown in the draw-

ings as being secured to one side of stock 1. However, the attachment may be secured in different positions upon the stock without departing from the spirit of the invention. The track 6 is provided with an upper flange 7 and a lower flange 8 that fit in the groove 9 of the slide 10, which slide is H-shape in cross section and is fixedly secured to one of the inside walls of the grip 11, Fig. 6. This grip 11 is substantially U-shape in cross section. The grip 11 is positioned under the stock 1 and can be easily grasped by the hunter or operator for moving the said grip back and forth as desired.

A cylinder 12 is provided, which has its inner 15 end positioned in a split clamp 13, Fig. 6. When the screws 14 are tightened upon clamp 13, the cylinder 12 will be securely gripped and held upon the clamp. The clamp 13 is provided with an integral plate-like extension 15 that lies flat against 20 one side of the grip 11. This flat extension 15 of the clamp has portions under two angle plates 15', Fig. 6. The extension 15 is held in an adjusted position by screw 16, which screw extends through the extension 15 and into the side of the 25 slide 11, as clearly seen in Figure 5. A link 17 is mounted on screw 16 and is also mounted on screw 18. The slotted clamp 13 has a swinging movement upon screw 16 and by moving screw 16 and 18 longitudinally of the grip 11, the position of 30 clamp 13 can be changed, as well as the cylinder 12.

The outer end of the cylinder 12 is flattened, producing a substantial square, Fig. 7. In this flattened end are two ball bearing devices 19, 35 each having a hub 20 extending into the aperture 21. A twisted or screw-like bar 22 slides between these two ball bearing devices 19 in an easy manner.

On the outer end of the screw-like bar 22 is a 40 link device 23. This device 23 is pivotally mounted on bar 22 at 24. The link device 23 comprises a bifurcated end 25, carrying the pivot 24, and has a substantially square shape shank 26 that extends through the ball 5. On the threaded extension 27 of the shank 26 is nut 28 that securely retains the link device 23 upon ball 5. A coil spring 29 is provided for assisting in closing the gun to a firing position; this spring 29 is fastened at its inner end to the lever 4 and is fastened 50 at its outer end to the gun barrel 2.

A grip device 30, Fig. 9, is provided for assisting the operator of the gun in retaining a firm hold upon the gun. This grip device comprises an outwardly bowed center 31 and flat ends 32, which 55 ends 32 are secured by a suitable means 33a to

the gun stock 1. The device 30 is fastened to the gun beyond the farthest movement of the grip 11.

As has been indicated hereinbefore, by placing the screws 16 and 18 and link 17 in different longitudinal positions on the grip 11, the spiral mechanism, including cylinder 12 and twisted bar 22, can be placed in various positions forward and rearward.

In operation, when it is desired to retract or slide bolt 3 outwardly, the operator grasps with one hand grip 11 and pulls rearwardly thereon which results in "opening" the gun. When it is desired to close the gun, that is force the sliding bolt 3 inwardly, the operator pushes outwardly upon grip 11 which causes the bolt 3 to have a slight side or rotary movement, resulting in the twisted bar 22 sliding between the ball bearing devices 19 within the cylinder 12 as the entire attachment assumes the position as shown in Figures 1 and 2. That is to say the closed position of the attachment is practically down on one side of the gun stock as shown. This downward movement from the open position is automatic. Therefore, it is to be understood that as the operator draws rearwardly upon grip 11, the action causes the attachment to take the position shown in Figures 3 and 4. Consequently, the peculiar and novel construction of the cylinder 12 and the twisted bar 22, with their cooperating parts, is necessary for the production of this efficient slide action attachment.

A section 33, Fig. 6, is suitably attached to the bottom of grip 11, and this section may be made of any material and roughened or grooved upon its sides to make an excellent surface to be gripped by the operator of the gun, when manipulating the attachment. Normally, one hand, and it is usually the left hand, is around the stock 1 and gun barrel 2 at the grip 30; this grip 30 affords great utility in the operator grasping the gun, while his other hand can be used to manipulate the grip 11.

While I have described the preferred embodiment of my invention and illustrated the same in the accompanying drawings, certain minor changes or alterations may appear to one skilled in the art to which this invention relates, during the extensive manufacture of the same, and I, therefore, reserve the right to make such alterations or changes as shall fairly fall within the scope of the appended claims.

What I claim is:

1. In a slide action attachment for bolt action guns having a bolt rotating lever, the combination of a grip and means slidably mounting said grip on the gun, a pair of plates secured to said grip, a clamp provided with an extension, said extension working between said plates, means pivotally securing said extension between said plates, a cylinder having one end mounted in said clamp, a twisted bar extending into the outer end of said cylinder, a link device on the outer end of said twisted bar, and said link device having a shank securely mounted upon the bolt rotating lever.

2. In a slide action attachment for bolt action guns having a bolt rotating lever, the combination of a grip and means slidably mounting said grip upon the gun, a cylinder and means pivotally mounting said cylinder on said grip, said cylinder provided with a pair of ball bearing devices in its outer end, a twisted bar working between said ball bearing devices, and means connecting said twisted bar to the bolt rotating lever.

3. In a slide action attachment for bolt action guns having a bolt rotating lever, the combination of a grip and means slidably mounting said grip upon the gun, a cylinder and means pivotally mounting said cylinder on said grip, said cylinder provided with a flattened outer end, a pair of ball bearing devices in said flattened outer end, each ball bearing device having a hub extending into a portion of said outer end of the cylinder, a twisted bar between said ball bearing devices, and means connecting said twisted bar to the bolt rotating lever.

4. In a slide action attachment for bolt action guns having a bolt rotating lever, the combination of a grip and means slidably mounting said grip upon said gun, a clamp being split at its upper end and provided with a plate-like extension, angle plates fastened to the side of said grip, said plate-like extension positioned between said angle plates, a screw extending through said plate-like extension and into a portion of said grip, a second screw extending into said grip, a link on said screws and engaging the outer face of said plate-like extension, a cylinder having one end in said clamp, said split end of the clamp being provided with screws whereby when the screws are tightened, the clamp will grip said cylinder, a twisted bar slidably extending into the outer end of said cylinder, and means connecting said twisted bar to said bolt rotating lever.

5. In a slide action attachment for guns, having a bolt rotating lever, a track fastened to a side of the gun, said track provided with flanges, a grip provided with a slide H-shape in cross section, said flanges on said track fitting said H-shape slide, a cylinder, a pivotally mounted clamp fitting a portion of said cylinder, means pivotally securing said clamp upon said grip, ball bearing means in said cylinder, a twisted bar engaging said ball bearing means, and means connecting said slide to the bolt rotating lever.
